UNITED STATES PATENT OFFICE

129,301

DESIGN FOR A SHIRT PRESSING MEMBER

Harry D. Forse, Anderson, Ind.

Application January 27, 1941, Serial No. 98,404

Term of patent 14 years

To all whom it may concern:

Be it known that I, Harry D. Forse, a citizen of the United States and a resident of Edgewood, Anderson, county of Madison, and State of Indiana, have invented a new, original, and ornamental Design for a Shirt Pressing Member, of which the following is a specification, reference being had to the accompanying drawing, forming part thereof.

In the drawing, Fig. 1 is a perspective view

of a shirt pressing member looking toward the pressing face thereof;

Fig. 2 is a side elevational view; and

Fig. 3 and Fig. 4 are opposite end elevational views, showing my new design.

I claim:

The ornamental design for a shirt presing member, as shown.

HARRY D. FORSE.
